UNITED STATES PATENT OFFICE

STACY B. HASELTINE, OF CHICAGO, ILLINOIS, ASSIGNOR TO W. H. MINER, INC., OF CHICAGO, ILLINOIS, A CORPORATION OF DELAWARE

CAR CONSTRUCTION

Application filed January 24, 1929, Serial No. 334,693. Renewed December 5, 1929.

This invention relates to improvements in car construction.

One object of the invention is to provide a combined locking and center pin arrangement for railway car bolsters, of rugged design, which may be readily applied and effectively locked against accidental removal, including a pair of locking elements having headed portions at opposite ends,

1. having shouldered engagement with the bolsters, and a central filler member for holding said elements separated, said filler member having means at the opposite ends thereof having shouldered engagement with the elements to lock the same together, said means at both ends of the filler member being of such a cross section that when the filler is in one position it will pass freely between said elements and when it is turned 20 to another position passage of said means between said elements is prevented.

A further object of the invention is to provide a center pin arrangement of the character indicated in the preceding paragraph, wherein means is provided for locking the filler member and the elements against relative rotation in their completely assembled condition.

Another object of the invention is to provide a combined locking and center pin arrangement for connecting the body and truck bolsters of a railway car having aligned center pin receiving openings and retaining shoulders adjacent said openings, 35 including a center pin comprising a pair of outer members and a filler, said outer members each having laterally projecting exterior flanges at opposite ends cooperating respectively with the shoulders of the body and truck bolsters, the flanges at corresponding ends of said members together defining head portions of the pin, the filler member maintaining the outer members separated to hold the flanges thereof in 40 overlapping relation with the retaining shoulders of the bolsters, the filler member being provided with retaining means at opposite ends thereof, engageable with the opposite ends of said outer members 45 to lock the parts together, the retaining

means at both ends of said filler member comprising pairs of lugs which, when registered with the opening between said outer members, will pass freely therebetween and when displaced angularly by rotation of said filler member will overlap the corresponding ends of said outer members.

55 A still further object of the invention is to provide a combined locking and center pin arrangement of the character indicated in the preceding paragraph, wherein the center pin receiving openings of the bolsters are slotted at opposite sides to accommodate portions of the flanges of the outer members, thus permitting the employment of flange members of relatively large size and great strength, thus adding greatly to the ruggedness of the center pin member.

60 Other and further objects of the invention will more clearly appear from the description and claims hereinafter following.

In the drawing, forming a part of this specification, Figure 1 is a top plan view of a portion of a body bolster of a railway car, 75 illustrating my improvements in connection therewith. Figure 2 is a vertical sectional view, corresponding substantially to the line 2-2 of Figure 1. Figure 3 is a horizontal sectional view, corresponding substantially 80 to the line 3-3 of Figure 2. And Figure 4 is a detailed perspective view of a retaining member employed in connection with my improved center pin construction.

In said drawing, the body bolster of the 85 car is designated by 10 and the cooperating truck bolster by 11. The bolsters proper may be of any suitable construction and, as shown, the body bolster is provided with the usual top and bottom webs connected by a 90 tubular section 12. At the bottom, the bolster 10 is provided with the usual bearing projection 13 which is of substantially spherical form and is seated in a cooperating bearing plate 14 which is mounted on 95 top of the truck bolster 11.

The truck bolster 11 is also provided with the usual top and bottom webs which are connected by transverse vertical walls defining a pocket 15.

In carrying out my invention, I provide the body bolster with a center pin receiving opening 16, and the truck bolster and bearing plate 14 mounted thereon with openings 17 and 18 in alignment with the opening 16 and of the same diameter, also adapted to accommodate the center pin member. The major portion of the tubular section 12 of the body bolster is of considerably greater diameter than the pin receiving opening 16, thereby providing a pocket to accommodate the upper head member of the center pin and an annular shoulder 19 at the bottom of the pocket which cooperates with the head of the pin.

The vertical walls of the truck bolster are spaced apart a distance greater than the diameter of the pin receiving opening 17 of said bolster, thereby providing an annular retaining shoulder 20 adjacent the pin receiving opening 17 at the upper end of the pocket 15. As will be evident upon reference to Figure 2, the shoulders 19 and 20 of the two bolsters are relatively close together, thereby permitting the use of a short center pin member.

My improved center pin proper comprises a pair of outer members A—A, a central filler or spacer B, and a retaining member C.

The members A are of similar design, and together form a substantially tubular outer section of the pin. Each of the members A is of arc shape horizontal cross section, as most clearly shown in Figures 1 and 3. At diametrically opposite sides of the center pin, the sections A are spaced apart, as clearly shown in Figures 1 and 3, to provide vertical passageways between said members, for a purpose hereinafter described. At the top and bottom ends, each member A is provided with laterally outwardly projecting horizontal flanges 21—21 which, when the parts of the pin are assembled, cooperate with the annular shoulders of the body and truck bolsters to lock the same together.

The flange members 21, at the upper ends of the members A, form a substantially complete head member at the top of the pin. The flanges 21, at the bottom ends of the members A, form a similar head member. The portions of the members A, between the heads 21, define the shank of the center pin and present exterior cylindrical surfaces which substantially fit the walls of the center pin receiving openings 16, 17 and 18. The center pin is provided with a central bore adapted to accommodate the filler member B, the opposed inner wall portions of the members A being recessed, as indicated at 22—22, to accommodate diametrically opposite sides of the shank portion of the member B. As most clearly shown in Figure 1, the flange members 21 of each member A are co-extensive with the main body portions of said members, thereby providing the center

pin with head portions of relatively heavy construction.

The filler member B comprises a cylindrical shank portion 23 which fits between the members A and has diametrically opposite side portions seated within the openings 22 of said members. At the bottom end, the shank 23 is provided with an enlarged portion forming a head member 24. The enlargement 24 comprises a pair of lugs at 75 diametrically opposite sides of the shank, which engage the bottom ends of the members A. At the upper end, the shank 23 of the member B is also provided with an enlargement 25 forming an upper head portion. The enlargement 25 comprises a pair of lugs disposed at diametrically opposite sides of the member B and in vertical alignment with the lugs of the head 24. The lugs of both heads are of such a width as to pass 85 freely through the passageways between the members A. When the filler member B is assembled with the members A, as illustrated in Figures 1, 2 and 3 of the drawings, the flanges 21 will be maintained in overlapped 90 relation with the shoulders 19 and 20 of the bolsters, thus locking the bolsters together. With the filler element positioned as shown in the drawings, the heads 24 and 25 thereof lock the members A together and prevent 95 relative movement of the members A and B with respect to each other in an endwise direction. As shown, the heads 24 and 25 closely fit the members A, thereby reinforcing the flanges 21. When the filler member 100 B is removed from between the members A, the latter may be displaced inwardly toward each other, thereby collapsing or contracting the pin so as to facilitate application and removal thereof.

The walls of the center pin receiving openings 16, 17 and 18 are recessed at diametrically opposite sides, as indicated by 26—26, to present vertical guide slots adapted to accommodate the inner extremities of the flanges 21 at opposite sides of each of the members A when the pin is collapsed or contracted. The parts of the pin are so proportioned that the members A may be successively inserted, each member 115 being of such a size that the outer edges of the flanges 21 at opposite ends thereof will clear the wall portions of the center pin receiving openings of the bolsters and the opposite inner end edges of each of said 120 flanges will pass through the openings 26, the curved end edges of these flanges being preferably concentric with the curved outer faces of the shank portions of the members A.

The retaining member C is in the form of a U-shaped clip having spaced arms 27—27 and a transverse connecting portion 28 at the upper end thereof. When the parts are assembled, the member C has the arms 27 130

thereof disposed on opposite sides of the shank of the filler member B within the guideways or openings between the members A.

5 As shown in Figures 2 and 4, the arms 27 are of such a length that they extend downwardly to the head 24 of the member B. The connecting section 28 of the retaining member C is supported on top of the head 25 of the member B, the head 25 being provided with a transverse seat 29 in which the transverse section is disposed. The bottom portions of the arms 27 are rounded on their outer sides, as indicated at 30-30, said 10 rounded portions lying in substantially the same cylindrical surface as the outer surfaces of the members A. The upper portions of the arms 27 are laterally enlarged, as indicated at 31-31, the enlarged portions being of such a length that the bottom portions thereof are seated in the recesses 26 of the side walls of the pin receiving opening 16. As will be evident, the arms 27 of the retaining member C being disposed between 15 the members A will be held against rotation with respect to the same, and the transverse upper section 28 being seated in the pocket 29 of the filler member B will hold the latter against rotation and all of the parts will 20 thus be locked together against relative rotation about the axis of the pin. It is further pointed out that by engagement of the lower end portions of the enlargements 31 within the recesses 26, the entire center pin structure will be locked against rotation with 25 respect to the bolster 10. The inner edges of the arms 27 are also rounded off so as to fit the opposite sides of the cylindrical shank portion 23 of the filler member B. In order 30 to facilitate the removal of the retaining member C, the same is provided with an upstanding central lug portion 32 having an opening 33 within which a removing tool may be engaged.

45 In applying the center pin to the bolsters 10 and 11, one of the members A is first inserted either through the body or truck bolster by passing the flange portion 21 at the corresponding end of the member A 50 through the pin receiving openings and bringing the flanges at the opposite ends thereof into cooperative relation with the corresponding annular shoulders of the two bolsters. This member is then displaced laterally outwardly to overlap the flanges with 55 the shoulders and bring the shank into contact with the corresponding side wall portions of the center pin openings. Sufficient clearance is thus provided to permit insertion 60 of the other member A. The latter is then inserted in a similar manner and displaced laterally outwardly to engage the flanges thereof with the retaining shoulders of the bolsters. When the members A have 65 been thus assembled with the bolsters and

spread apart, sufficient clearance is provided between the same to accommodate the filler member B. The filler member B is then inserted between the members A by passing the same upwardly through the pocket of 70 the truck bolster or downwardly through the pocket of the body bolster. At this time, the lugs forming the heads 24 and 25 are so disposed as to register with the passageways between the members A. When 75 the filler has been fully inserted so that the heads 24 and 25 are disposed respectively below and above the corresponding ends of the members A, the filler member is given a quarter turn so as to dispose the lugs forming the heads 24 and 25 as shown in Figures 80 1 and 2. When the heads are thus positioned, the parts A and B are locked against relative displacement in an endwise direction and the members A are held in their outer- 85 most position with the flanges thereof overlapping the shoulders of the body and truck bolsters. The retaining member C is then applied by passing the same through the pocket of the body bolster and engaging 90 the arms 27 thereof within the passageways at diametrically opposite sides of the pin between the members A.

The retaining element is passed downwardly until the transverse section 28 thereof is seated within the pocket 29 of the head 25. As hereinbefore pointed out, all of 95 the parts of the pin are thus locked against relative rotation. When the retaining member has been fully applied, the enlargements 100 31 of the arms will engage within the recesses 26, as hereinbefore pointed out, thereby preventing rotation of the center pin with respect to the body bolster. Although 105 the center pin has been described and shown 110 as locked to the body bolster, it will be evident that my invention is not limited to this precise construction and that the enlargements 31 of the retaining member may be omitted, thereby allowing relative rotation 115 of the center pin structure as a unit with respect to both bolsters. With the enlargements 31 omitted, the arms 27 will be locked between the members A and the retaining member will be locked to the filler B by the 120 transverse section 28, thus interlocking all of the parts of the pin against relative rotation.

In removing the center pin so that the body and truck bolsters may be separated, the retaining member C is first withdrawn, whereupon the filler member B may be rotated to bring the lugs at the opposite ends thereof into registration with the passageways between the members A and the filler member withdrawn either upwardly through the body bolster or downwardly through the truck bolster. After removal of the filler member, one of the members A may be moved inwardly toward the other 125 130

so as to contract or collapse the head portions of the pin formed by the flanges 21 thereof and permit withdrawal of the displaced member. After removal of said member, the other member A is displaced laterally inwardly to register the flanges thereof with the openings and guideways so as to permit withdrawal of the same.

While I have herein shown and described what I consider the preferred manner of carrying out my invention, the same is merely illustrative and I contemplate all changes and modifications which come within the scope of the claims appended hereto.

I claim:

1. In car construction, the combination with body and truck bolsters having aligned center pin openings, each bolster having a shoulder adjacent its opening; of a center pin including a plurality of sections and a filler member for holding said sections apart, said sections each having means at the opposite ends thereof adapted to overlap and engage the shoulders of said bolsters, respectively, said filler member having a head at one end, the shape of said head being such that it may be inserted between said sections in one position, but is prevented from passing therebetween when given a partial turn to prevent removal of said member in one direction, said filler member having means at the other end to prevent removal in the opposite direction.

2. In car construction, the combination with body and truck bolsters having aligned center pin receiving openings, each bolster being provided with a shoulder adjacent its opening; of a sectional center pin including a pair of outer members and a removable spreading member therebetween, said outer members having enlargements at the opposite ends cooperating with the shoulders of the body and truck bolsters, respectively, said enlargements forming the heads at the opposite ends of the center pin, the parts of said members intermediate the heads forming the shank of said pin and fitting within the openings of the bolsters, said pin being collapsible when said spreading member is removed to permit contraction of the heads of said pin to allow passage of the same through the center pin receiving openings of the bolsters, said spreading member having heads at opposite ends cooperating with the opposite ends of said outer members to lock the parts of said pin together against endwise relative movement, said heads being of such a shape in cross section as to pass between said outer members when registered with the openings therebetween and to overlap the corresponding ends of said outer members when given a partial turn.

3. In car construction, the combination with body and truck bolsters having aligned center pin openings; of a sectional center

pin including a removable filler member adapted to hold said sectional pin expanded, said filler member when removed allowing collapse of the pin, said pin having flange portions at opposite ends thereof forming heads having shouldered engagement with the bolsters to prevent removal of the pin, said heads being contracted when said pin is collapsed to permit passage of each of the heads through the pin receiving openings, said filler member having means thereon for holding the sections of said pin against separation in a lengthwise direction, said filler member in one position being insertible between said sections and being held against removal when angularly displaced to bring said holding means into operative relation; and means for locking the pin sections and the filler member against relative angular displacement.

4. In car construction, the combination with body and truck bolsters having aligned center pin openings, each bolster being provided with a shoulder adjacent its opening; of a sectional center pin including a pair of outer sections and a removable spacer therebetween, said pin being contractable when said spacer is removed, said outer sections being held apart by said spacer and having means at opposite ends thereof cooperating with the shoulders of said bolsters respectively, for locking the pin to the bolsters, said means being contractable with said sections to permit passage of said means through the pin receiving openings, said spacer having heads at opposite ends engageable with the opposite ends of said sections to lock the same against relative displacement in a lengthwise direction, one of said heads being in the form of diametrically opposed lugs adapted to pass through the openings between said sections, said lugs engaging over the corresponding ends of said sections when said spacer is given a partial turn to interlock the sections of the pin.

5. In a car construction, the combination with body and truck bolsters having aligned center pin receiving openings; of a center pin including a pair of outer members and a central cylindrical spacer, each of said outer members having enlargements at opposite ends thereof, the enlargements at corresponding ends forming head members of the pin, said head members having shouldered engagement with the respective bolsters to prevent removal of the pin, said outer members being spaced apart at diametrically opposite sides of the pin to provide passageways, said spacer having heads at opposite ends thereof, each head comprising a pair of diametrically opposite lugs adapted to pass through the passageways when in registration therewith, said spacer being rotatable to dispose the lugs

in overlying relation to said outer members to lock the parts of the pin against relative displacement in an endwise direction, said spacer when removed permitting collapse of said outer members to contract the head portions of the pin to permit insertion and withdrawal of either of the heads through said pin receiving openings.

6. In car construction, the combination 10 with body and truck bolsters having aligned center pin receiving openings, each of said openings having a retaining shoulder adjacent thereto; of a center pin including a pair of outer members and a central cylindrical spacer, each of said outer members having flanges at opposite ends thereof, the flanges at corresponding ends forming head members of the pin, said head members respectively engaging the shoulders of the 15 body and truck bolsters to prevent removal of the pin, said outer members being spaced apart at diametrically opposite sides of the pin to provide passageways, said spacer having a head at one end and a pair of 20 diametrically opposite lugs at the opposite end adapted to pass through said passageways when in registration therewith, said spacer being rotatable to dispose said lugs in overlying relation to said outer sections to 25 lock the parts of the pin against relative endwise displacement, said spacer when removed permitting collapse of the outer members of the pin to contract the head portions to permit insertion and removal of 30 said heads through the pin receiving openings, opposite side wall portions of said pin receiving openings being recessed to provide clearance for said flanges.

7. In car construction, the combination 35 with body and truck bolsters having aligned center pin receiving openings, each of said openings having a retaining shoulder adjacent thereto; of a center pin including a pair of outer members and a central cylindrical spacer, each of said outer members having flanges at opposite ends thereof, the flanges at corresponding ends forming head members of the pin, said head members respectively engaging the shoulders of the 40 body and truck bolsters to prevent removal of the pin, said outer members being spaced apart at diametrically opposite sides of the pin to provide passageways, said spacer having a head at one end and a pair of diametrically opposite lugs at the opposite ends 45 adapted to pass through said passageways when in registration therewith, said spacer being rotatable to dispose said lugs in overlying relation to said outer sections to lock 50 the parts of the pin against relative endwise displacement, said spacer when removed permitting collapse of the outer members of the pin to contract the head portions to permit insertion and removal of said heads 55 through the pin receiving openings, oppo-

site side wall portions of said pin receiving openings being recessed to provide clearance for said flanges; and a U-shape retaining member for locking said spacer to said outer members to prevent relative rotation of the parts of the pin, said retaining member also being interlocked with one of the bolsters to hold the pin against rotation with respect to the same.

8. In car construction, the combination 70 with body and truck bolsters having aligned center pin openings and each provided with a shoulder adjacent its opening; of a center pin composed of outer sections and a removable central filler member, said outer sections each having enlargements at opposite ends forming head portions cooperating with said shoulders of the body and truck bolsters to lock the bolsters together, said enlargements at corresponding ends of said sections together forming a head member of the pin, said outer sections being displaceable toward each other when said filler member is removed to effect contraction of the pin to reduce the size of said head members, said pin receiving openings of the bolsters being recessed at diametrically opposite sides to provide clearance for the corresponding sides of the contracted head portions of said outer sections of the pin.

9. In car construction, the combination 75 with body and truck bolsters having aligned center pin openings each provided with a shoulder adjacent its opening; of a center pin composed of a two-part outer tubular portion and a cylindrical filler member fitting within said tubular portion to hold the parts thereof expanded, each of said parts of the tubular portions having flanges at opposite ends engageable respectively with the shoulders of said body and truck bolsters, said parts of the tubular member being spaced apart at diametrically opposite sides of the pin to provide passageways, said cylindrical filler member having heads at opposite ends thereof cooperating with the opposite end portions of said tubular member to prevent endwise displacement of the parts thereof, one of said heads of the filler member being in the form of diametrically opposed enlargements adapted to pass through said passageways when registered therewith, and adapted to interlock with said tubular part of the pin when said filler is given a partial rotation.

10. In car construction, the combination 100 with body and truck bolsters having aligned center pin openings, each bolster having a shoulder adjacent its opening; of a center pin having shouldered engagement at opposite ends with the shoulders of said bolsters, said pin including inner and outer members, said inner member holding said outer members spaced apart and having head elements at opposite ends thereof, and said 105

outer members having portions thereof interposed between the heads of the central member and the shoulders of the bolsters and having shouldered engagement with said heads and shoulders of the bolsters respectively to prevent removal of the pin, the head at one end of said central member being of such a shape that it will pass between said outer members when said central member is in one position, but is prevented from passing therebetween when given a partial turn to lock the pin to the bolsters.

11. In car construction, the combination with body and truck bolsters having aligned center pin openings, each bolster having a shoulder adjacent its opening; of means for connecting said bolsters including a plurality of members, one of said members having a shank extending through said bolsters, said shank having head elements at opposite ends thereof, said other members embracing the shank of said first named member and being spread apart thereby and having portions thereof interposed between each head member and the corresponding shoulders of the bolsters and having shouldered engagement with the head elements to prevent removal of the first named member, the head element at one end of the latter being of such a shape that it will pass between the embracing members when said central member is in one position, but is prevented from passing therebetween when given a partial turn to provide said shouldered engagement with the embracing members.

In witness that I claim the foregoing I have hereunto subscribed my name this 21st day of January 1929.

STACY B. HASELTINE.
